Gelston Sanford

UNITED STATES PATENT OFFICE.

GELSTON SANFORD, OF NEW YORK, N. Y.

HORSE-POWER.

Specification of Letters Patent No. 31,090, dated January 8, 1861.

To all whom it may concern:

Be it known that I, GELSTON SANFORD, of the city, county, and State of New York, have invented a new and Improved Horse-
5 Power; and I do hereby declare that the following is a full and exact description thereof, reference being had to the accompanying drawings, and to the letters of reference marked thereon, in which—

10 Figure 1 is an elevation, Fig. 2 a plan view, Fig. 3 a vertical cut section, Fig. 4 is an elevation showing the bevel wheels and pulley shaft below the line of draft, Fig. 5 a plan view showing bevel wheels and shaft 15 also below the line of draft, Fig. 6, a vertical cut section with bevel wheels and shaft below the draft line and bed or lower frame.

The object of my invention is to make a horse power that will be equal to any other, 20 while it occupies much less ground room by elevating the driving pulleys sufficiently high to be out of the way of the operator as shown in Fig. 1.

The frame L with rim J is so constructed 25 that by unscrewing the bolts by which it is held to the bed, the frame L can be turned around, so that the belt-pulley can be turned to run a shaft set at different relations to the main bed of the driving machinery. If 30 a planter or farmer wishes to drive more than one shaft, for operating different machinery, set at different relations to the bed frame, by these devices I can apply my belt to any machinery simply by revolving the frame L, 35 thus bringing the belt-pulley in such a position as to apply the driving belt to machinery at any point wished, without the expense of moving the whole of the machinery. In cases of powers not revolving like mine, 40 it is a great expense of time and labor to effect the purpose thus obtained so easily and readily by these devices, or if desired the bevel wheel G can be attached to the shaft E, below the driving power as shown in 45 Fig. 4.

My invention consists in resting an internal gear wheel B, on three or more rollers

C, and keeping it in place with three or more intermediate wheels D having fixed centers which obviates having an eye or boring or turning out their centers; 2d in constructing the vertical frame L, and ring J in such manner that they can be set for driving the shaft I to operate machinery set at any angle to the machine; 3d by placing the beveled wheels G and H below lower frame or bed of the machine for the purpose of constructing a stationary power into a portable one.

A is the bed or lower frame which can be 60 fastened to the floor of any building or to the ground.

B is the internal gear wheel which rests upon rollers C. The wheel is kept in its place with wheels D which have fixed centers. The wheel B also has receptacles on its upper-side for securing shafts for the purpose of attaching horses or other power to operate the machine.

E is the vertical shaft to which is secured 70 cog wheel F which gears into wheels D thereby causing shaft E to revolve which operates bevel gear wheel G which gears into bevel gear H which is attached to and operates shaft I to which is attached driving pulleys. 75

J is a ring fastened to spider K by screws, and can be set to revolve the vertical frame L to any position to the lower or bed frame A. Frame L can be fastened by the hole in the cross-head and allowed to be turned in 80 any direction without affecting its rigidity.

What I claim as my invention and desire to secure by Letters Patent is—

The manner of arranging the frame L, rim J, and spider K; with the bed frame 85 A of the machine, for the purpose of revolving the frame L and belt-pulley, so that the power can be applied to a shaft or shafts standing in different relations to the driving machine, as set forth, and described.

GELSTON SANFORD.
